MEANS FOR PREVENTING ACCUMULATION
OF ICE ON AIRPLANES OR THE LIKEHarry E. Waner, Akron, Ohio, assignor to The
B. F. Goodrich Company, New York, N. Y., a
corporation of New York

Application May 22, 1934, Serial No. 726,876

2 Claims. (Cl. 244—31)

This invention relates to devices for preventing accumulation of ice on surfaces exposed to ice-forming conditions, such as the wing, control and other surfaces of an airplane.

Heretofore inflatable rubber "shoes" have been mounted upon such surfaces for this purpose, but in a direction transverse to the air-stream they have been of rectilinear form and although a plurality of inflatable tubes have been mounted side-by-side in parallel relation and have been inflated and deflated in succession in order to provide dissymmetry of cross-section for unbalancing pieces of ice held in place by the force of the air-stream, the operation of such devices has not always resulted in the breaking of the ice into pieces as small as might be desired and adequately unbalancing the pieces for their immediate removal by the air-stream.

The chief objects of my invention are to provide a device of this general character adapted to be highly effective in breaking the ice into small pieces, and especially by breaks extending in various directions, and to provide a dissymmetry of the surface of the device such as to be more effective in unbalancing the pieces of ice with respect to the force of the air-stream.

A further object is to provide these advantages with a single distensible container as distinguished from a plurality of containers requiring to be distended in alternation or succession.

Of the accompanying drawing:

Fig. 1 is a perspective view of tail portions of an airplane having mounted upon the leading edges of its vertical and horizontal stabilizers embodiments of my invention in its preferred form.

Fig. 2 is a section on line 2—2 of Fig. 1.

Fig. 3 is a perspective view, with parts in section, of one of the devices in flat condition, apart from the airplane.

The device in the preferred form here shown comprises a base layer 10 of rubberized fabric, a cover layer 11 of rubberized fabric, the two being vulcanized to each other, face to face, along their margins, and, mounted between them and vulcanized to them, two tubes of rubber or rubberized fabric 12, 13 each of which is of periodic increasing and decreasing size in cross-section, large portions of each one lying alongside small portions of the other, the two tubes at each position lengthwise thereof being of what may be termed complementary cross-sectional size and their adjacent sides being disposed along a sinuous line 14.

The device preferably is anchored to the under-

lying surface of the airplane only at its margins and in order to prevent the force of the air-stream from causing it to wrinkle it is desirable that it be mounted on the airplane with the base layer 10 under substantial transverse tension such as could not be readily obtained by simply cementing the margins to the airplane surface. To that end one longitudinal margin of the device is provided with a strip of fabric 15 vulcanized to the under side of the base layer 10 and having 10 its opposite face substantially free of rubber so that it can be firmly anchored to the airplane surface by a suitable cement, and the opposite longitudinal margin of the base layer 10 has vulcanized thereto a strip of fabric 16 provided 15 with lacing eyelets 17, 17 for lacing it to a similar fabric strip 18 which is adapted to be cemented to the airplane surface and is provided with eyelets 19, 19.

The device being first secured along its upper 20 margin (Fig. 2) to the airplane by the cementing of the strip 15 in place and the strip 18 being cemented in place, the base layer 10 can then be strongly tensioned, after the cement has dried, by lacing the strips 16 and 18 together, after 25 which the free margin of the cover sheet 11 can be cemented in place as a fairing over the lacing.

While my invention is not wholly limited to this feature, the two tubes 12 and 13 in this embodiment are in communication with each other, 30 within the container constituted by the base sheet 10 and cover sheet 11, and a single fluid conduit 20, connected to suitable fluid-pressure and exhaust devices (not shown), is provided for inflating them concurrently and deflating them con- 35 currently.

In the operation of the device the inflation thereof causes distension of the tubes 12 and 13 and a flexing and stretching of the cover sheet 11, and, because of the varying cross-sectional 40 size of the tubes, or the holding down of the cover sheet along the sinuous line 14, such flexing and stretching of the cover sheet is of non-uniform and quite varied character at different positions lengthwise and at different positions cross-wise 45 of the device, so that the ice is broken into small pieces by the "squirming" action, and also, by reason of the tubes or expansion zones being of varying size the pieces of ice are unbalanced with relation to the force of the air-stream and are 50 "blown" away, without the necessity of alternate or successive inflation and alternate or successive deflation of a plurality of tubes.

A reversal of the change of shape of course occurs upon deflation of the device, by reason of 55

its resilience, and when another quantity of ice has gathered upon its retracted surface the distending action is repeated.

I claim:

5. 1. Apparatus for preventing accumulation of ice on aircraft comprising an elongate, distensible container, means for maintaining relatively close proximity of opposite walls thereof along a sinuous line, and means for conducting pressure-

fluid into and venting it from the container to vary its shape.

2. Apparatus for preventing accumulation of ice on aircraft comprising two distensible tubes of varying cross-section mounted side by side 5 with large portions of each opposite small portions of the other and means for conducting pressure-fluid into and venting it from said tubes.

HARRY E. WANER.
